HOOD ORNAMENT

Hy C. Hammer, Chicago, Ill., assignor to Compco Corporation, Chicago, Ill., a corporation of Illinois

Application August 10, 1949, Serial No. 4,395

Term of patent 14 years

(Cl. D14—18)

To all whom it may concern:

Be it known that I, Hy C. Hammer, a citizen of the United States, residing at Chicago, county of Cook, and State of Illinois, have invented a new, original, and ornamental Design for a Hood Ornament, of which the following is a specification, reference being had to the accompanying drawing forming a part thereof, in which Figure 1 is a perspective view of a hood ornament embodying my design; Fig. 2, a plan view of the same; Fig. 3, a view in side elevation thereof; Fig. 4, a front elevational view of the same; and Fig. 5, a rear elevational view of the same.

I claim:

The ornamental design for a hood ornament, as shown.

HY C. HAMMER.
